INDICATING DEVICE FOR ELECTRIC CLOCKS

Max Menkin, New York, N. Y.

Application July 2, 1940, Serial No. 343,519

2 Claims.

(CL 58—26)

This invention relates to indicating devices for electric clocks and has for its general object and purpose to provide a simply constructed and reliably operating device for indicating an interruption of the electric current for a sufficient period of time to impair the accurate timing function of the clock mechanism.

It is a more particular object of the invention to provide such an indicating device for electric clocks of the self-starting, synchronous motor driven type in which the accurate time keeping qualities of the clock are dependent on the freedom from interruption of the alternating motor energizing current.

It is a characteristic feature of the present invention to provide an indicating device for the above purpose embodying a movable indicating element which is normally active while the clock motor is uninterruptedly supplied with energizing current and becomes inactive to indicate a failure of the current when the current flow to said motor is interrupted, but without influencing the continuity of flow of the current to the motor field and the operation of the clock mechanism in either condition of said indicating element.

In a practical embodiment of the invention, I prefer to employ a vari-colored rotatable indicating element and to provide a synchronous magnetic field for operating said element by extending several of the laminations of the clock motor field core to form pole pieces so that, after initial manual rotation of the indicating element, it will thereafter be maintained active by the continuous supply of current to said motor, and upon interruption in the current supply of the slightest duration, rotation of said indicating element will cease. Thus the attention is called to the fact, after the supply of current has been resumed and the operation of the clock continued, that the indicated time is inaccurate and that the clock should be reset.

With the above and other objects in view, the invention consists in an indicating device for electric clocks, and in the combination and arrangement of the several parts, as will be hereinafter described, illustrated in the accompanying drawing and subsequently incorporated in the subjoined claims.

In the drawing wherein I have illustrated one simple and practical embodiment of the invention and in which similar reference characters designate corresponding parts throughout the several views:

Fig. 1 is a front elevation, partly broken away

showing one practical form of the indicating device.

Fig. 2 is a vertical sectional view, taken substantially on the line 2—2 of Fig. 1.

Fig. 3 is a rear elevation, the rear cover plate being removed, and

Fig. 4 is a horizontal sectional view taken substantially on the line 4—4 of Fig. 2.

Referring in detail to the drawing, 10 generally indicates an electric clock of the self-starting type, which may be of any suitable or preferred construction well known in the art. For the purpose of this explanation, it is deemed necessary to show only sufficient of the clock mechanism 15 as will enable the application and operation of my present invention to be clearly understood. Therefore, it will suffice to state that the clock includes the outer casing 6 of any desired ornamental form, within which the self-starting alternating current synchronous motor 7 is suitably mounted to operate the clock mechanism indicated at 8. This motor includes the field core 9 of the coil 10, said core being of the usual soft iron laminated construction and having the 25 pole pieces indicated at 11.

The indicating device, in the form selected for illustration, includes a shaft or spindle 12 suitably mounted or supported in the clock case for free rotation and having one end thereof 30 extended rearwardly through an opening in the rear cover plate 13 of the case and provided with a suitable finger piece 14 whereby said shaft may conveniently be manually rotated. To the forward end of this shaft and adjacent the rear 35 face of the dial plate 15 of the clock an indicating disk 16 is fixed. The front surface of this disk is provided with radially extending, alternating, contrastingly colored areas visible through the opening 17 in the dial plate 15. As 40 an example, I may provide the surface of said disk with white areas 18 alternating with the red areas 19. Also, I preferably provide said disk with the serpentine or undulating perimeter 20 which is likewise visible through the opening 45 17. This feature, in connection with the vivid color contrast between the surface areas 18 and 19, attracts the attention of the observer to said rotating disk in the normal operation of the clock.

After the rotation of the indicating disk 16 is 50 started by the manual operation of the shaft 12, magnetic means is provided for continuing the rotation of said disk while there is an uninterrupted supply of alternating electric current to the motor 7. In one simple and practical embodiment of this magnetic operating means for the

indicator, I form several of the laminations of the stator or field core 9 of the motor 7 with the extensions 21, which, as herein shown, extend vertically above the parallel side legs of said core and terminate at their upper ends in the inwardly projecting spaced apart pole pieces 22. The inner edges of these pole pieces are closely spaced in concentric relation from a magnetizable disk or rotor 23 fixed upon the shaft 12, the confronting edges of said disk and pole pieces being toothed in the conventional manner, as shown. At one side of the disk 23, a fly wheel 24 is loosely mounted on the shaft 12, suitable connecting means (not shown) being interposed between said disk and fly wheel. As the use of such fly wheel is commonly employed in this art, further detail description thereof is not required. Its purpose is to insure the continued active operation of the indicator as the notches of the pole pieces 22 and disk 23 register with each other.

In the operation of the above described device, it will be understood that when operating current is supplied to the motor 7, a magnetic flux field is established between the pole pieces 22 and after the disk 16 has been initially rotated by manual operation of the shaft 12, said magnetic field causes the rotation of said shaft and the disk 16 so long as the supply of operating current to the motor 7 is not interrupted. However, upon the slightest interruption in the current supply, the rotation of the shaft 12 will cease and the disk 16 will be stationary or inactive, which condition may be noted by the observer through the opening 17. When the supply of current is again resumed, the construction of the pole pieces and interposed rotor prevents movement of the indicating device, while the full current supply to motor 7 again operates the clock mechanism. The fact that the indicating disk 16 is not moving or rotating, informs the observer that there has been an appreciable interruption in the current and that the indicated time is inaccurate. The clock is then reset and the shaft 12 manually operated so that the indicating function of the disk 16 is again established.

It will thus be seen that I have provided a simple and reliably operating indicating device which is actively influenced by the motor energizing current so long as the motor is uninterruptedly supplied with said current and that the said device is instantly rendered inactive upon inter-

ruption of the current supply, but without influencing the continuity of the flow of current to the motor and the operation of the clock mechanism in either condition of the said indicating device. I have disclosed my novel indicator, in one application thereof, to a self-starting electric clock, but it will be more or less obvious that the invention is not necessarily limited to such application as it may also be applied in various other instances where there is a likelihood of interruption in the supply of electric energy to an electrically driven instrument. Likewise, the invention is not limited in its essentials to the particular practical embodiment of the combination and arrangement of cooperating elements which I have selected for purposes of illustration, but is manifestly susceptible of embodiment in numerous other structural forms. Accordingly, I reserve the privilege of resorting to all such legitimate changes in these respects as may be fairly comprehended within the spirit and scope of the appended claims.

I claim:

1. In combination with a clock and a self-starting synchronous operating motor therefor, a rotatable indicating element associated with the clock, and magnetic control means therefor operatively influenced by the motor field to continuously rotate said element in one direction while the current supply to the motor is maintained and to render said element inactive upon current interruption and after the current supply and operation of the clock is re-established.

2. In combination with a self-starting clock including timing mechanism and an operating rotor therefor, a current-failure indicating element and an operating rotor therefor, and a synchronous clock motor having means for producing a single magnetic field for energizing both of said rotors to continuously actuate said timing mechanism and indicating element while the current supply to the motor is maintained, said rotors being so constructed and arranged relative to the magnetic field that only the first named rotor is re-energized upon resumption of current supply after failure, while said second named rotor and indicating element are again continuously actuated by the motor field only after initial manual rotation is imparted to the latter rotor.

MAX MENKIN.
